UNITED STATES PATENT OFFICE

160,946

DUPLICATING MACHINE

Guilbert M. Hunt, Euclid, Ohio, assignor to Addressograph-Multigraph Corporation, Cleveland, Ohio, a corporation of Delaware

Application October 3, 1949, Serial No. 5,278

Term of patent 14 years

(Cl. D64—11)

To all whom it may concern:

Be it known that I, Guilbert M. Hunt, a citizen of the United States, residing in Euclid, State of Ohio, have invented a new, original, and ornamental Design for a Duplicating Machine, of which the following is a specification, reference being had to the accompanying drawings, forming a part hereof:

Fig. 1 is a front perspective view of a duplicating machine showing my new design; Fig. 2 is a rear perspective view of the same; and Fig. 3 is an elevational view of the opposite side to that shown in Figs. 1 and 2.

I claim:

The ornamental design for a duplicating machine, as shown.

GUILBERT M. HUNT.
